UNITED STATES PATENT OFFICE

149,292

DESIGN FOR A BUILDING

Arthur T. Moore, Fayetteville, N. C.

Application November 4, 1946, Serial No. 134,512

Term of patent 14 years

(Cl. D13—1)

To all whom it may concern:

Be it known that I, Arthur T. Moore, a citizen of the United States, residing at Fayetteville, in the county of Cumberland and State of North Carolina, have invented a new, original, and ornamental Design for a Building, of which the following is a specification, reference being had to the accompanying drawing, forming part thereof.

Fig. 1 is perspective view of the front and one side of a building, showing my new design;

Fig. 2 is a perspective view of the back and one side of the building;

Fig. 3 is a top plan view of the building in reduced scale.

I claim:

The ornamental design for a building, substantially as shown.

ARTHUR T. MOORE.
